(57) **CLAIM**

The ornamental design for a roof for an automotive vehicle, as shown and described.

DESCRIPTION

FIG. 1 is a perspective view of a roof for an automotive vehicle, showing the new design in a closed configuration; the opposite view of the roof is a symmetrically mirrored image of FIG. 1;

FIG. 2 is a top elevational view of the roof showing the new design in a closed configuration;

FIG. 3 is a rear elevational view of the roof showing the new design in a closed configuration;

FIG. 4 is a side elevational view of the roof showing the new design in a closed configuration; and,

FIG. 5 is a perspective view of the roof showing the new design in an open configuration. The broken line illustration of a portion of the automotive vehicle is for illustrative purposes only and forms no part of the claimed design.
